[57] CLAIM

The ornamental design for a hinged top card file, as shown and described.

DESCRIPTION

FIG. 1 is a perspective view of a hinged top card file showing our new design;

FIG. 2 is an exploded perspective view thereof;
FIG. 3 is a top plan view thereof with the cover portion omitted;

FIG. 4 is a bottom plan view thereof;

FIG. 5 is a rear elevational view of the hinged top card file with the cover in closed position.

The interior surfaces of the cover are smooth plane surfaces.
